CLAIM

I claim the ornamental design for a folder, as shown and described.

DESCRIPTION

FIG. 1 is a front/right/bottom perspective view of a folder, shown with the front surface curled from upper right to lower left;

FIG. 2 is a front/right/bottom perspective view of the folder;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a view of the folder in an open configuration.

The dash-dot lines represent the bounds of the claimed design. The broken lines that are extensions of solid lines (where the solid lines transition to become the broken lines) and the broken lines adjacent the margins of the pages represent the bounds of the claimed design, while all other broken lines are directed to environment and are for illustrative purposes only. The broken lines form no part of the claimed design.
